US0D1101067S

(12) **United States Design Patent** (10) **Patent No.:** **US D1,101,067 S**
(45) **Date of Patent:** **** Nov. 4, 2025**

(54) **MODEL CAR**

(71) Applicant: **Junjie Huang**, Shenzhen (CN)

(72) Inventor: **Junjie Huang**, Shenzhen (CN)

(**) Term: **15 Years**

(21) Appl. No.: **29/902,159**

(22) Filed: **Sep. 8, 2023**

(30) **Foreign Application Priority Data**

Aug. 28, 2023 (EM) 015032318-0001

(51) **LOC (15) Cl.** **21-01**

(52) **U.S. Cl.**

USPC **D21/549**; D21/548; D21/533

(58) **Field of Classification Search**

USPC D21/484, 560, 550, 533, 419, 427, 433,
D21/552, 557, 548, 549, 559, 561, 434,
D21/537, 424, 428; D12/562, 82, 83, 88,
D12/93

CPC . A63H 17/004; A63H 30/04; A63H 2017/055

See application file for complete search history.
